UNITED STATES PATENT OFFICE

LOUIS S. MORSE, OF YORK, PENNSYLVANIA, ASSIGNEE TO YORK ICE MACHINERY CORPORATION, OF YORK, PENNSYLVANIA, A CORPORATION OF DELAWARE

ICE CAN

Application filed June 25, 1930. Serial No. 463,700.

This invention relates to refrigeration, and particularly to ice cans.

The object of the invention is to produce a can unit, preferably a multiple can unit, in which a single part serves two functions.

5 During the freezing operation it serves to position the drop pipes through which air for purpose of agitation is supplied. At the commencement and termination of the freezing 10 operation, it serves for the attachment of a grapple or lifting structure by means of which a can unit is lowered into the brine tank and removed therefrom.

15 The preferred embodiment of the invention is illustrated in the accompanying drawings, in which

Figure 1 is a perspective view of a four-can unit suspended by the improved lifting means.

20 Fig. 2 is a perspective view on a reduced scale showing how the air manifold and drop pipes are mounted in the can unit after the lifting means has been removed.

Fig. 3 is a side elevation of the lifting bar.

25 Fig. 4 is a longitudinal section thereof showing the construction.

Fig. 5 is a fragmentary view showing how the lifting bar is moved into and out of engagement with the lifting yoke on the can unit.

30 Fig. 6 is a view similar to Fig. 5 showing the yoke in lifting position.

It will be understood that any number of cans may be combined in a single unit, but 35 for purposes of illustration, a four-can unit is illustrated. The cans are indicated generally by the reference numeral 11. Each can has a mouth band 12 which is riveted or otherwise connected to the mouth of the can 40 and reinforces the same. Between the first and second cans, and also between the third and fourth cans, there are inserted plate-like members 13. The cans are held together and the members 13 are held in position by rivets 45 14 which pass through the mouth bands 12 of both cans and through the member 13. The second and third cans are held together by rivets 15 which pass directly through the mouth bands 12 of these two cans. The 50 lower portions of the cans are held in spaced

relation and protected against bulging by an encircling band 16 which is suspended by the straps 17 from the mouth bands 12 of the end cans. There are suspended straps 17 on both ends of the can unit.

55 There are cross members 18 extending through the space between each pair of adjacent cans and connected at their opposite ends to the band 16.

The members 13 are provided near their opposite ends with notches 19 for a purpose not concerned with the present invention, and each has at its middle a notch made up of a relatively narrow slot 21 which merges into an enlargement, preferably circular, indicated at 22.

60 When the can unit is filled and in place in the brine tank, the two recesses 22 serve to position the manifold pipe 23 to which a plurality of drop pipes 24 are connected. The 70 connection is by means of releasable clamps whose form is not material to the present invention. Air is supplied to the manifold 23 through a flexible hose connection 26 (see Fig. 2). It will be observed that the pipe is 75 so dimensioned that it will pass through the narrow slot into the recess and that the curved bottom of the recess will approximately center the manifold pipe.

At or before the completion of the freezing 80 operation, the drop pipe 24 and the manifold 23 are removed as is usual in the art, and when the cans have been completely frozen they are lifted out by a grapple structure which enters the openings 22 through 85 the slot 21 and after a partial rotation may not be withdrawn through the slot 21. This grapple comprises a tubular bar 31 into the ends of which are inserted grapple members 32 which are offset downwardly as indicated 90 at 33. Below each offset is a lug 34 whose configuration is best shown in Fig. 5. In end view it is approximately semi-circular and has a curvature conforming to the circular curvature of the opening 22. The lower face 95 35 is not strictly flat but is slightly bowed or convex as indicated in Figs. 5 and 6.

Surrounding each end of the tubular bar 31 are sleeves 36 each of which is connected to the tubular bar 31 and to a corresponding 100

one of the members 32 by a rivet 37. Each sleeve 36 is provided with apertured lugs 38 between which the end link of a chain 39 is received. The bolt 41 passed through the lugs 38 holds the chain in position. There are two chains 39, one for each sleeve, and these chains are connected to any suitable hoisting means represented by the block 42.

To engage the lifting member with the lifting plates 13, the bar is canted to the position shown in Fig. 5, at which time the lugs 34 will pass through the slots 21 and into the circular opening 22.

If the bar be turned 90° so that the lugs 38 assume upright positions the lugs 34 fill the upper half of the opening 22 and thus cannot pass back through the slot 21. If the block 42 be lowered sufficiently it is a simple matter to strike the lugs 34 into the notches 21 allowing them to drop to the bottom of the opening 22. Thereafter by merely hoisting through the block 42 the bar 31 may be caused to rotate and assume the position shown in Fig. 6. After the can unit has been lowered to a position of rest the block 42 is further lowered whereupon the grapple bar 31 will turn or may be turned by hand to a position such as that shown in Fig. 5 at which time the lugs 34 may be lifted through the slots 21.

The offsets 33 serve two functions. They engage with the plates 13 and prevent end-wise motion of the bar 31 and its connected parts; also their effect and the effect of the offset produced by the upward extending lugs 38 is cumulative so that when freely suspended the bar 31 tends to assume the position indicated in Fig. 6.

The mechanism described is simple and inexpensive to construct, and is capable of being manipulated with ease and rapidity. Furthermore, the grapple structure introduces no complications in connection with the air manifold. The location of the air manifold is imposed by the necessity that each drop pipe be located accurately at the center of its can. The grapple should also be centered to balance the unit. The provision of a simple structure which will meet both these requirements and in which a single notch 50 serves not only to center the grapple but also to position the drop pipe manifold offers marked advantages and is a decided advance in the art.

I claim:

1. Lifting means for can units comprising in combination with such unit, a pair of spaced lifting members mounted on the unit and each having a slot extending from an edge thereof and terminating in an enlargement; suspending means; a bar normally pendant from said suspending means; and lugs carried by said bar, said lugs being so proportioned that in the normal pendant position of the bar the lugs are incapable of passing through said slots, but are ren-

dered capable of passing through when the bar is tilted about its longitudinal axis.

2. Lifting means for can units comprising in combination with such unit, a pair of spaced lifting members mounted on the unit 70 and each having a slot extending from an edge thereof and terminating in a circular enlargement; suspending means; a bar normally pendant from said suspending means; and lugs carried by said bar and having a 75 substantially semi-circular cross section, said lugs being so positioned that in the normal pendant position of the bar the lugs are incapable of passing through said slots, but are rendered capable of passing through when 80 the bar is tilted about its longitudinal axis.

3. Lifting means for can units comprising in combination with such unit, a pair of spaced lifting members mounted on the unit and each having a slot extending from an 85 edge thereof and terminating in an enlargement; suspending means; a bar normally pendant from said suspending means; and downwardly offset lugs carried by said bar, the offsets serving to engage said lifting members to position the bar longitudinally and the lugs having one face flattened and being so arranged relatively to the bar that they are incapable of passing through said slots in the normal pendant position of the 90 bar and capable of passing through said slots when the bar is tilted about its longitudinal axis.

4. The combination defined in claim 1 further characterized in that said slots are 100 centered on the center line of the top of the can unit, and are dimensioned to permit the passage of an air manifold pipe into said enlargements for support and alinement thereby.

5. The combination defined in claim 1 further characterized in that the lifting members are plates fixed between the sides of adjacent cans, and project above the cans.

In testimony whereof I have signed my 110 name to this specification.

LOUIS S. MORSE.
